UNITED STATES PATENT OFFICE.

E. IRVING ROGERS, JR., OF PROVIDENCE, RHODE ISLAND.

DESIGN FOR A COLLAR-HOLDER.

57,863.

Specification for Design. Patented May 10, 1921.

Application filed October 27, 1920. Serial No. 420,032. Term of patent 7 years.

To all whom it may concern:

Be it known that I, E. IRVING ROGERS, Jr., a citizen of the United States, residing at Providence in the county of Sumter and State of Rhode Island, have invented a new, original, and ornamental Design for a Collar-Holder, of which the following is a specification, reference being had to the accompanying drawing, forming part thereof.

Fig. 2 is a front view of the same.

I claim:

The ornamental design for a collar holder as shown.

E. IRVING ROGERS, Jr.
